UNITED STATES PATENT OFFICE.

SOLOMON ROSEFSKY, OF BROOKLYN, NEW YORK.

DIAPHRAGM HORN OR ALARM.

1,025,998.

Specification of Letters Patent. Patented May 14, 1912.

Application filed October 22, 1910. Serial No. 588,431.

To all whom it may concern:

Be it known that I, SOLOMON ROSEFSKY, a citizen of the United States, residing at Brooklyn, in the county of Kings and State of New York, have invented certain new and useful Improvements in Diaphragm Horns or Alarms; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in horns, signals, alarms, and the like; and the invention relates, more particularly, to a novel construction of horn, or the like, in which the sound is accomplished by mechanically agitating a diaphragm to generate sound waves of high penetrating quality.

The principal object of the present invention is to provide a simple and efficient construction of alarm horn, or the like, of few parts and simple in operation.

A further object of this invention is to provide a novel means for agitating the sound wave producing diaphragm; and, furthermore, a means whereby said agitating means may be easily adjusted to cause the production of the desired note or tone of said alarm-horn.

Other objects of this invention not at this time more particularly enumerated will be clearly understood from the following detailed description of the present invention.

With the various objects of the present invention in view, the said invention consists, generally, in the novel construction of alarm-horn, or the like, hereinafter set forth; and, the invention consists, furthermore, in the novel arrangements and combinations of the various devices and parts, as well as in the details of the construction of the same, all of which will be more fully described in the following specification, and then finally embodied in the clauses of the claim which are appended to and which form an essential part of the said specification.

The invention is clearly illustrated in the accompanying drawings, in which:

Figure 1 is a side view or elevation of the novel construction of alarm-horn, or the

like, made according to and embodying the principles of the present invention, the sound amplifying horn-body being shown in longitudinal section; Fig. 2 is a rear-end view of the same; and, Fig. 3 is a horizontal cross-section of the same taken on line 3—3 in said Fig. 2, looking in a downwardly direction.

Similar characters of reference are employed in all of the herein-above described views to indicate corresponding parts.

Referring now to the several figures of the drawings, the reference-character 1 indicates the complete alarm-horn, or the like, made according to and embodying the principles of this invention, the said alarm-horn, or the like, comprising a shell-like body or casing 2 being open at one end, said shell-like body or casing being provided with an outwardly extending annular flange 3, the inner side of which forms a seat. Said annular flange being in turn provided at its periphery with a rim or flange 4 extending at right angles thereto. Arranged upon said seat, formed by said annular flange 3, so as to extend across the opening of said shell-like body or casing 2 is a diaphragm 5, the marginal edges 6 of which may be secured to said flange 3 by means of solder 7, or other suitable fastening means. The reference-character 8 indicates a cover-member provided with an opening 9 registering over or above said diaphragm 5. Said opening 9 is surrounded by a suitable shoulder or collar 10 extending outwardly from the outer face of said cover-member. Said cover-member 8 is further provided at its periphery with a rim or flange 11 extending at right angles thereto, and adapted to engage and be secured to said rim or flange 4 connected with the flange 3 of said shell-like body or casing 2 to properly inclose or cover said diaphragm. Arranged in the body of said member 8 are a plurality of screws 12, or other similar fastening devices, the same being adapted to engage the margins of said diaphragm 5 to serve as an additional holding means for firmly binding said diaphragm upon the seat formed by said flange 3 of said shell-like body or casing 2. Secured to said cover-member 8 in any suitable manner is an outwardly extending bracket-piece 13, by means of which said alarm-horn may be supported in a proper location upon a vehicle or other place where it is desired

to use the same. Secured by means of set-screws 14, or any other suitable fastening means, upon said shoulder or collar 10 of said cover-member is the neck of an amplifying horn or megaphone 15, so arranged that it registers with said opening 9 over or above said diaphragm 5, the purpose of said horn or megaphone being clearly apparent as a means for amplifying concentrating and directing the sound waves generated by said diaphragm 5. Said diaphragm 5 is provided with a pair of agitating-elements, each comprising a foot-piece or base 16 adapted to be secured to and abut against the rear or inner side of said diaphragm 5, a rearwardly extending arm 17 connected with said foot-piece, and a contact-finger 18 connected with the free end of said arm 17. The means for securing said foot-piece or base in its proper relation with said diaphragm consists, preferably, of a pair of studs or shanks 19 adapted to be passed through holes or openings in the body of said diaphragm arranged for their reception, and the free ends of the same then being riveted over in the form of a retaining-head 20 upon the opposite surface of said diaphragm 5. Each of said rearwardly extending arms 17 is provided with a hole or opening 21 the inner edges of which are formed with a chamfer 22 adapted to provide a seat for the head 23 of an adjusting pin 24. The free end of said adjusting pin 24 extends through a suitable opening in the walls of said shell-like body or casing 2, provided for that purpose, and said free end is provided with a suitable screw-thread 25 upon which is arranged an adjusting-nut 26 which bears against the outer surface of said shell-like body or casing 2. One of the sides of said shell-like body or casing 2 is provided with a hole or opening the marginal edge of which is provided with an outwardly extending shoulder or collar 27. Arranged in said hole or opening and secured to said shoulder or collar by means of suitably arranged retaining screws 28, or the like, is the casing 29 of a small electric motor 30. Said casing 29 being provided with suitably arranged binding-posts 31 for securing in proper connection the current supplying or conveying wires 32. The armature of said motor rotates a shaft 33 mounted in suitable bearing pieces 34 arranged in connection with said motor-casing 29. One end of said shaft 33 extends inwardly into the interior of said shell-like body or casing 2. Secured in any suitable manner upon said inner end of said shaft 33, which is within said shell-like body or casing 2, is a vibrator-wheel 35, having upon its periphery any desired number of cam-members 36. Said vibrator-wheel 35 is arranged in such a manner that when the same rotates its cam-members 36 are

brought into contact with said contact-fingers 18 of said agitating elements, whereby the same are caused to vibrate in a manner to transmit such vibrations to said diaphragm 5, so that the latter is in turn agitated or vibrated to produce the desired sound-waves. It will be clearly evident from an inspection of Fig. 3 of the accompanying drawings, that the adjusting means, comprised in said adjusting pins 24 and their respective nuts 26, may be so operated as to move a greater or less portion of said contact-fingers 18 into the path of said cam-members 36 of said vibrator-wheel 35, whereby a greater or less vibration or agitation of said diaphragm 5 may be brought about and a consequent regulation of the pitch or tonal sound waves produced by said diaphragm may be obtained. It will thus be evident that the novel alarm-horn, or the like, may be tuned to produce the desired sound having the desired degree of penetrability and carrying power sufficient to produce a proper alarm. It will, furthermore, be understood that the leverage of the agitating elements which are secured upon said diaphragm tends to the production of decisive and sharp vibration of said diaphragm whereby a distinctive character is given to the sound wave produced by said vibration, the same being peculiarly adapted to give the warning desired to be produced.

I am fully aware that changes may be made in the various arrangements and combinations of the several devices and parts, as well as in the details of the construction of the same without departing from the scope of my present invention, as described in the foregoing specification and as defined in the claims which are appended thereto. Hence, I do not limit my invention to the exact arrangements and combinations of the various devices and parts as set forth in the said specification, nor do I confine myself to the exact details of the construction of the said parts as illustrated in the accompanying drawings.

I claim:

1. An alarm-horn, or the like, comprising a casing, a diaphragm secured over the open end of said casing, agitating elements connected with said diaphragm, each comprising, a foot-piece provided with means for rigidly securing the same to said diaphragm, a rearwardly extending arm connected with said foot-piece, a contact-finger connected with the free end of said arm, a means arranged within said casing for vibrating said agitating elements, comprising an electric motor, a vibrator-wheel connected with the shaft of said motor and rotated thereby, said vibrator-wheel being provided with a plurality of cam-portions adapted to engage with said contact-fingers of said agitating elements when said vi-

vibrator-wheel is rotated, and means for regulating the contact of said contact-fingers with said cam-portions of said vibrator-wheel, comprising an adjusting pin loosely connected with said rearwardly extending arm of each agitating element, said adjusting pin being adapted to pass through a suitable opening in said casing, screw-threads on the free ends of said adjusting pins, and adjusting-nuts arranged upon said screw-threads.

2. An alarm-horn, or the like, comprising a casing open at one end, a flange providing a diaphragm seat at the open end of said casing, a diaphragm secured upon said seat and extending across the open end of said casing, a cover-member provided with an opening secured upon the open end of said casing and extending in front of the outer face of said diaphragm, a horn or megaphone, means connected with said cover-member for supporting said horn or megaphone in registration with said opening of said cover-member, agitating elements connected with said diaphragm, each comprising, a foot-piece provided with means for rigidly securing the same to said diaphragm, a rearwardly extending arm connected with said foot-piece, a contact-finger connected with the free end of said arm, a means arranged within said casing for vibrating said agitating elements, comprising an electric motor, a vibrator-wheel connected with the shaft of said motor and rotated thereby, said vibrator-wheel being provided with a plurality of cam-portions adapted to engage with said contact-fingers of said agitating-elements when said vibrator-wheel is rotated, and means for regulating the contact of said contact-fingers with said cam-portions of said vibrator-wheel, comprising an adjusting pin loosely connected with said rearwardly extending arm of each agitating element, said adjusting pin being adapted to pass through a suitable opening in said casing, screw-threads on the free ends of said adjusting pins, and

adjusting-nuts arranged upon said screw-threads.

3. In an alarm-horn, the combination with 50 a casing of a diaphragm, agitating elements connected with said diaphragm, each comprising, a foot-piece provided with means for rigidly securing the same to said diaphragm, a rearwardly extending arm connected with said foot-piece, a contact-finger connected with said arm, a vibrator-wheel arranged to rotate within said casing and in contact with said contact-fingers of each agitating element, and means for regulating 60 the contact of said contact-fingers with said vibrator-wheel, comprising an adjusting pin loosely connected with said rearwardly extending arm of each agitating element, said adjusting pin being adapted to pass 65 through a suitable opening in said casing, screw-threads on the free ends of said adjusting pins, and adjusting-nuts arranged upon said screw-threads.

4. In an alarm-horn, the combination, with 70 a casing of a diaphragm, rearwardly extending arms rigidly connected with said diaphragm, contact-fingers connected with said arms, a rotatable vibrator-wheel, cam-portions on said vibrator-wheel adapted to 75 travel in the path of and in contact with said contact-fingers when said vibrator-wheel is rotated, and means for regulating the contact of said contact-fingers with said cam-portions of said vibrator-wheel, comprising 80 adjusting pins loosely connected with each rearwardly extending arm, said adjusting-pins being adapted to pass through suitable openings in said casing, screw-threads on the free ends of said adjusting pins, and adjusting-nuts arranged 85 upon said screw-threads.

In testimony, that I claim the invention set forth above I have hereunto set my hand this 19th day of October, 1910.
